United States Patent Office

Des. 198,341
Patented June 2, 1964

198,341

JUG OR SIMILAR ARTICLE

Louis K. Warden, Laguna Beach, Calif., assignor to Purex Corporation, Ltd., Lakewood, Calif., a corporation of California

Filed Sept. 14, 1962, Ser. No. 71,690

Term of patent 14 years

(Cl. D58—5)

FIG. 1.

FIG. 2.

FIG. 4.

FIG. 3.

FIG. 5.

FIG. 1 is a view showing in side elevation a jug embodying my new design;

FIG. 2 is a right end elevation of FIG. 1;

FIG. 3 is a left end elevation of FIG. 1;

FIG. 4 is a top plan view of FIG. 1; and

FIG. 5 is a bottom plan view of FIG. 1.

I claim:

The ornamental design for a jug or similar article,
substantially as shown.
